UNITED STATES PATENT OFFICE.

BENJAMIN FRANKLIN NIXON, OF WINNIPEG, MANITOBA, CANADA.

VESSEL INDICATING AND RAISING APPARATUS.

1,223,606.

Specification of Letters Patent.

Patented Apr. 24, 1917.

Application filed May 2, 1916. Serial No. 94,981.

To all whom it may concern:

Be it known that I, BENJAMIN F. NIXON, a subject of the King of Great Britain, residing at Winnipeg, in the Province of Manitoba and Dominion of Canada, have invented certain new and useful Improvements in Vessel Indicating and Raising Apparatus, of which the following is a specification, reference being had therein to the accompanying drawing.

This invention relates to vessel indicating and raising apparatus and has for its principal object the production of a simple and efficient means for designating the position in which the wrecked ship rests upon the bottom of the sea, ocean, or other body of water.

Another object of this invention is the production of a vessel indicating and raising apparatus wherein simple and efficient guide means is employed for directing the lifting elements downwardly into the interior of the sunken ship.

Another object of this invention is the production of a vessel indicating and raising apparatus wherein a plurality of jaws are pivotally mounted upon the deck of the ship so as to allow the lifting elements to pass therebeneath after which the jaws may be swung to a closed position so as to grip the elements whereby the sunken ship may be raised.

With these and other objects in view this invention consists of certain novel combinations, constructions, and arrangements of parts as will be hereinafter fully described and claimed.

In the accompanying drawings:

Figure 1 is an elevation of the vessel indicating and raising apparatus, illustrating the manner in which the same is used for lifting the sunken ship.

Fig. 2 is a fragmentary side elevation of a submarine boat, partly broken away, illustrating the connecting and locking mechanism carried thereby in elevation and also in section.

Fig. 3 is a top plan view of the locking mechanism showing the jaws in a closed position.

Fig. 4 is a top plan view of the locking mechanism showing the jaws in an open position.

Fig. 5 is a side elevation of the locking

mechanism showing the supporting deck and housing therefor in section.

Fig. 6 is a section taken on the line 6—6 of Fig. 3.

Fig. 7 is a fragmentary sectional view through a portion of the float and connecting cable positioned therein.

Fig. 8 is a fragmentary sectional view through a portion of the device, illustrating the manner in which the locking bar is employed for normally retaining the float upon the float housing.

Fig. 9 is a fragmentary sectional view through the cable reel and float housing, illustrating the manner in which the conductor wires are connected to the cable.

Referring to the accompanying drawing by numerals it will be seen that the vessel indicating and raising apparatus has been disclosed herein in connection with a submarine 1, although it is of course, obvious that it may be used in connection with any other form of a boat or ship. The deck 2 of the submarine 1 is provided with a number of openings 3 formed therein and supports thereon the elongated casing 4 having an internal flange 5 formed thereon for supporting the cap 6.

It will be seen by referring particularly to Fig. 2, that the cap 6 has a base 7 formed at a distance from the inner portions of the cap. Upon the base 7 there is formed an air tank 8 depending for a considerable distance therebelow. The tank housing 9 used in connection with the air tank 8 is positioned upon the inner portions of the submarine 1 so as to engage the lower surface of the deck 2 as clearly shown in Figs. 2, 5, and 6. The diagonal braces 10 are secured to the under surface of the deck 2 and also to the tank housing 9 adjacent the lower portions thereof in any suitable manner so as to positively retain the tank housing in its correct position preventing at any time its accidental displacement. Upon the lower portions of this tank housing there is carried a cap 11 for closing the lower end, as shown in Fig. 2. Thus, it will be seen that under normal conditions when the air tanks are in their correct positions upon the submarine they will extend into the interior of the tank housing 9. Each tank housing 9 is provided with the enlarged bearings 12 formed in alignment with each other,

through which the hollow shaft 13 is adapted to extend, this shaft also extending through the lower portion of the tank housing 9. This hollow shaft has the end plates 14 carried thereon within the tank housing whereby the shaft 13 and plates 14 will constitute a reel upon which the elongated cable 15 is normally wound. This elongated cable 15 is connected to the eye 16 of the rivet 17 carried by the lower portions of the air tank 8, so that when the air tank floats upon the surface the cable will, of course, be unwound from the reel above described.

In case the submarine or other ship accidentally sinks to the bottom one of the air tanks 8 may be released. It is, of course, obvious that when the device is in use in connection with a submarine as herein disclosed it is necessary to positively lock the air tanks in set positions so as to prevent the same from floating when the submarine is running submerged. Therefore, upon one side of each tank there is provided a lug 16 into which the locking bar 17 normally extends, as shown clearly in Fig. 8. This locking bar has a pin 18 extending through the slotted lever 19 which lever is pivotally mounted upon the lug 20 depending from the lower surface of the deck 2 of the submarine. The rear end of the locking bar 17 is provided with a head 21 which is adapted to reciprocate within the cylinder 22, which is secured by the blocks 23 or in any other suitable manner to the lower portions of the deck 2. Thus, it will be seen that when the submarine accidentally sinks to the bottom the lever 19 may be gripped and swung away from the housing 9 thereby withdrawing the locking bar 17 from the lug 16, thereby releasing the air tank 8. Because of the buoyancy of the cap 6 and the air tank 8, it will be seen that the air tank may immediately rise to the surface, thus causing the cable 15 to unreel from the cable reel until the air tank reaches the surface of the water. It is, of course, obvious that if so desired an intake passage may communicate with the interior of the forward end of the cylinder 22 so that if this device is used in connection with an ordinary surface navigating vessel when the vessel sinks the sea water may pass through the passage and into the forward end of the cylinder 22 so as to exhaust the air from the rear end the head 21 is driven from the rear end of the cylinder 22, whereby the bar 17 may be automatically withdrawn from engagement with the tank 8 thus allowing the tank to float.

In order to allow communication with the surface of the water by the occupants of the sunken boat or ship, the hollow shaft 13 is provided with the metallic blocks 24, which are insulated from engagement with each other by the insulated washers 25. The collars 26 are also insulated from each other by

the insulated washers 25, although they communicate with the blocks 24 so that the wires 27 may also be electrically connected to these blocks 24. The wires 28 extending from the blocks 24 extend through the cable 15, and thus when the air tank which constitutes the float is taken on to the rescue ship a telephone may be connected to the ends of the wire which may be detached from the eye 16 so as to allow communication to be had with the interior of the sunken ship or vessel, owing to the fact that the wires 27 are in turn connected to a telephone 29 of any suitable construction which is suspended, as shown at 30 from the lower portion of the deck 2 of the submarine or other vessel 1.

The rescue ship 31 shown in Fig. 1, is provided with a derrick 32 having the arm 33 pivotally connected thereto, and this arm 33 carries the counterbalancing weight 34. After the air tank has been removed from the surface of the water the cable 15 may be secured to the outer end of the weighted arm 33 and then passed over the supporting standard 35 to a point within the vessel so as to allow communication, as above set forth, to be had with the occupants of the sunken vessel. It will be seen that the function of the weighted arm 33 is to hold the cable 15 taut as shown in Fig. 1 so as to cause the cable 15 to constitute a direct guide into the interior of the submarine or sunken vessel 1. The lifting cable 36 extends over the outer end of the bearing 32 and has the finger 37 of the ball 38 secured thereto. This finger 37 and ball 38 are provided with a longitudinal passage 39 through which the cable 15 may be passed when it is being taken on to the collier or rescuing vessel 31, so that as the lifting cable 36 is paid out from the collier 31 the ball 38 will be directed downwardly along the cable 15 into the interior of the tank housing which is open because of the release of the air tank.

Upon the deck 2 of the submarine 1 and adjacent each opening 3 formed therein, there is positioned a supporting plate 39. This plate 39 is riveted, as shown at 40, or otherwise secured to the upper portion of the deck 2 so as to be positioned within the elongated casing 4, as shown in Figs. 3 and 4. The plate 39 is provided with a central opening 41 registering with the openings 3 formed in the deck 2, thereby allowing the ball 38 to pass into the tank housing 9. The jaws 42 and 43 are carried upon the shafts 44 extending through the plate 39. One of the shafts 44 has a squared portion so as to allow the particular shaft 44 to be rotated by means of the grip 45 positioned upon the upper portion of the submarine and engaging the lower end of the shaft, as shown clearly in Figs. 5 and 6. The rear ends of the jaws 42 and 43 are provided with the racks 46 which mesh with each other, as

shown in Figs. 3 and 4, so that when the shaft 44 having the squared portion is rotated by means of the grip 45, the jaw 43 will be swung to a closed position and the meshing of the racks 46 will also swing the jaw 42 to a closed position. It is obvious that at this time the ball 38 will be extending partially through the opening 3 formed in the deck 2 of the submarine, as shown clearly in Figs. 5 and 6, so as to allow the sockets 47 to receive the finger 37. At this time the pinion 48 resting upon the plate 39 and meshing with one of the racks 47 will also be rotated so as to swing the pin 49 carried thereby in a circle. The supporting post 50 has the slotted link 51 pivotally mounted thereon so as to allow the pin 49 to extend through the slot 52 formed therein. Adjacent the opposite end from the pivoted 20 end of the link 51 there extends a second pin 53 carried by the reinforcing plate 54. This reinforcing plate 54 is passed between the shafts 44 and is held in central alignment with the sockets 47 when the jaws 42 and 43 are in a closed position. Therefore, it will be seen that as the pinion 48 is rotated the pin 49 thereof will swing the free end of the link 51 over the jaws. This action will cause the pin 53 working in the slot 30 52 to move the reinforcing plate 54 forwardly, thus causing the plate to finally engage the finger 37, as shown clearly in Fig. 3, when the jaws are in a closed position, thus further retaining the finger within the sockets 47 formed in the jaws 42 and 43. After the jaws 42 and 43 have been moved to a closed position it will be seen that the offset forward end 55 of the jaw 43 will fit upon the free forward end of the jaw 42, 40 which extends in the same plane throughout its entire length. At this time the locking lugs 56 and 57 formed upon the forward ends of the jaws 43 and 42 respectively will register with each other, although the lug 56 is formed at a distance below the upper plane of the offset end 55 as shown clearly in Fig. 6. At this time the pinion 58 keyed upon the shaft 59 may be rotated by means of the grip 60 upon the interior of the submarine 1. Of course, it will be seen that as this pinion 58 is rotated it will drive the locking slide 61 owing to the fact that this pinion 58 meshes with the side rack 62 formed upon the locking slide 61. This locking slide has the pin 63 passing through the slot 64 and, furthermore, as soon as this slide passes through the retaining strap 65 it will be held in a central position so as to allow its offset lip 66 to fit upon the lugs 56 and 57, thereby positively holding the jaws 42 and 43 from accidentally opening or having any tendency to move in such a direction. It will also be noted that a retaining strap 67 extends across the rear ends 65 of the jaws 42 and 43, so as to allow the up-

per ends of the shafts 44 to be pivotally mounted thereon, while the ends of both straps 65 and 67 are secured by means of the rivets 68 to the plate 39. It is further obvious that the upper ends of the shafts 44 and 59 may be squared as shown at 69, so that in case it is desired to move the reinforcing plate and locking slide to grip the finger upon the outer portions of the ship, as where a diver descends, exterior force 75 may be supplied by a wrench or any other suitable means to the squared ends 69 thus moving the locking elements to the positions for gripping the finger 37, thereby positively holding the finger so as to allow the 80 lifting cable 36 to raise a sunken boat or ship.

From the foregoing description it will be seen that a very efficient vessel indicating and raising apparatus has been provided, 85 which is so formed as to normally be carried in a very compact position upon a submarine or other boat or ship, so that when not in use it will not be in the way. However, when a submarine sinks, the air tank 90 constituting the float may be released so as to float, or when used in connection with an ordinary vessel, the air tank may automatically float thus paying the cable out so that communication may be had with the interior 95 of the vessel, while the cable will further constitute a guide for directing the lifting elements or means into the interior of the vessel. Therefore, after this action it will be seen that the locking elements may be 100 brought to a locked position so as to grip upon the finger of the lifting elements or means, thereby positively holding these lifting elements in engagement with the sunken ship, so that as power is applied, the sunken 105 ship may be raised to the surface and after this action it will be seen that the cable 15 may be rewound upon the reel by means of the crank grip 70 keyed upon the hollow shaft 13.

What is claimed is:

1. In a device of the class described, the combination of a plate, said plate being adapted to be carried upon the deck of a vessel, a float normally extending through said plate into the interior of said vessel, a cable connected to said float and extending into the interior of the vessel, whereby when the vessel sinks the float may rise to the surface so as to pay out said cable, said cable being adapted to direct a ball having a finger downwardly into the vessel, locking jaws pivotally mounted upon said plate, means for swinging said locking jaws to a closed position, and a locking slide mounted upon said plate, said locking slide being adapted to engage the forward ends of said jaws when the jaws are in a closed position, thereby positively holding said jaws in a gripping engagement with the finger of said ball,

whereby as said finger and ball are raised the sunken vessel may also be raised.

2. In a device of the class described, the combination of a plate, said plate being adapted to be secured to the deck of a vessel, said plate having a central opening, a float carried upon said plate and extending through said opening into the interior of the vessel, a cable carried by said float and extending into the vessel whereby when the vessel sinks the float may rise to the surface so as to allow the cable to be paid out, whereby a lifting ball and finger may be directed downwardly along said cable through the opening formed in said plate, rotating shafts carried by said plate, locking jaws mounted upon said shafts, said jaws having intermeshing racks at their rear ends, whereby as the shafts are rotated the jaws may be swung to a closed position, said jaws having sockets adapted to receive said finger, one jaw having an upwardly offset end for fitting over the remaining jaw when the jaws are in a closed position, whereby the finger may be positively gripped so as to cause the sunken boat or vessel to be lifted as the finger and ball are raised.

3. In a device of the class described, the combination of a plate, said plate being adapted to be secured to the deck of a vessel, said plate having a central opening, a float carried upon said plate and extending through said opening into the interior of a vessel, a cable carried by said float and extending into the vessel, whereby when the vessel sinks the float may rise to the surface so as to allow the cable to be paid out, whereby a lifting ball and finger may be directed downwardly along said cable through the opening formed in said plate, rotating shafts carried by said plate, locking jaws mounted upon said shafts, said jaws having intermeshing racks at their rear ends, whereby as the shafts are rotated the jaws may be swung to a closed position, said jaws having sockets adapted to receive said finger, one jaw having an upwardly offset end for fitting over the remaining jaw when the jaws are in a closed position, a locking plate slidably mounted upon the rear end of said jaws, means for simultaneously moving said locking plate over the rear ends of said jaws as the jaws are swung to a closed position, whereby when the jaws are closed said plate may bear upon the finger for positively reinforcing said jaws and also stably retaining the finger.

4. In a device of the class described, the combination of a plate, said plate being adapted to be secured to the deck of a vessel, said plate having a central opening, a float carried upon said plate and extending through said opening into the interior of the vessel, a cable carried by said float and extending into the vessel, whereby when the

vessel sinks the float may rise to the surface so as to allow the cable to be paid out, whereby a lifting ball and finger may be directed downwardly along said cable through the opening formed in said plate, rotating shafts carried by said plate, locking jaws mounted upon said shafts, said jaws having intermeshing racks at their rear ends, whereby as the shafts are rotated the jaws may be swung to a closed position, said jaws having sockets adapted to receive said finger, one jaw having an upwardly offset end fitting over the remaining jaw when the jaws are in a closed position, a locking plate slidably mounted upon the rear ends of said jaws, means for simultaneously moving said locking plate over the rear ends of said jaws as the jaws are swung to a closed position, whereby when the jaws are closed said plate may bear upon the finger for positively reinforcing said jaws for positively retaining the finger, and a locking slide carried upon said plate and being adapted to engage the forward ends of said jaws for resisting any tendency of said jaws to swing to an open position when the boat or vessel is being raised by the upward movement of said ball and finger.

5. In a device of the class described, the combination of a plate having an opening, said plate being adapted to be carried upon the deck of a ship, a float normally carried by said plate and extending through said opening into the interior of the ship, a cable carried by said float and extending into the interior of the ship whereby when the float rises to the surface the cable will be paid out, said cable being adapted to direct a ball and finger downwardly through the opening in said plate, shafts rotatably mounted upon said plate, jaws keyed upon said shafts, intermeshing racks formed upon the rear ends of said jaws, whereby as one shaft is rotated the jaws may be swung to a closed position, a pinion rotatably mounted upon said plate and meshing with one of said racks, a pin carried by said pinion, a slotted link pivotally mounted upon said plate, said pin of said pinion extending into the slot of said link, a reinforcing plate slidably mounted upon the rear ends of said jaws, a pin carried by said reinforcing plate extending through said slot of said link, whereby as the jaws are swung to a closed position said pinion will be rotated so as to swing the free end of the reinforcing plate forwardly, whereby as the jaws engage the finger of said ball the reinforcing plate will also engage the finger so as to reinforce said jaws, whereby as the finger and ball are moved upwardly the sunken ship may also be raised.

6. In a device of the class described, the combination of a plate having an opening, said plate being adapted to be carried upon

the deck of a ship, a float normally carried by the vessel and extending through said opening into the vessel, a cable carried by said float and extending into the vessel, whereby when the float rises to the surface the cable will be paid out, said cable being adapted to direct a ball and finger downwardly through the opening of said plate, shafts rotatably mounted upon said plate, jaws keyed to said shafts, intermeshing racks formed upon the rear ends of said jaws, whereby as one shaft is rotated the jaws may be swung to a closed position, a pinion rotatably carried upon said plate and meshing with one of said racks, a pin carried by said pinion, a slotted link pivotally mounted upon said plate, said pin of said pinion extending into the slot of said link, a reinforcing plate slidably mounted upon the rear ends of said jaws, a pin carried by said reinforcing plate extending through the slot of said link, whereby as the jaws are swung to a closed position said pinion will be rotated so as to move the free end of the reinforcing plate forwardly thereby moving said reinforcing plate over the inner ends of said jaws, whereby as the jaws engage the finger of said ball the reinforcing plate will also engage the finger so as to reinforce the finger, and means for engaging the forward ends of said jaws for resisting any tendency of their accidental displacement, whereby as the finger and ball are moved upwardly the sunken vessel may be raised.

7. In a device of the class described, the combination of a plate having an opening, said plate being adapted to be carried upon the deck of a ship, a float normally carried by the plate and extending through the opening into the vessel, a cable carried by said float, and extending into the vessel, whereby when the float rises to the surface the cable will be paid out, said cable being adapted to direct a ball and finger downwardly through the opening of said plate, shafts rotatably mounted upon said plate, jaws keyed upon said shafts, intermeshing racks formed upon the rear ends of said jaws, whereby as one shaft is rotated the jaws may be swung to a closed position, a pinion rotatably mounted upon said plate and meshing with one of said racks, a pin carried by said pinion, a slotted link pivotally mounted upon said plate, said pin of said pinion extending into the slot of said link, a reinforcing plate slidably mounted upon the rear ends of said jaws, a pin carried by said reinforcing plate extending through the slot of said link, whereby as the jaws are swung to a closed position said pinion will be rotated so as to move the free end of the reinforcing plate forwardly, thereby moving said reinforcing plate over the forward end of said jaws, whereby as

70
75
said jaws engage the finger of said ball the reinforcing plate will also engage the finger so as to reinforce said jaws, and lugs formed upon the forward end of each jaw, whereby when the jaws are in a closed position the lugs may register with each other, a locking slide carried upon said float and provided with an upwardly offset end, means for moving said slide into engagement with said lugs, whereby said jaws will be positively held from accidentally swinging to an open position, thereby allowing the sunken vessel to be raised as the finger and ball are lifted.

8. In a device of the class described, the combination of a pair of gripping jaws, means for supporting said jaws, said jaws having intermeshing racks at their inner ends, and means for swinging one of said jaws toward a closed position, whereby said racks will swing the remaining jaw toward a closed position, thereby causing said jaws to simultaneously clamp upon an article. 80 85

9. In a device of the class described, the combination of a pair of gripping jaws, means for supporting said jaws, said jaws having intermeshing racks at their inner ends, means for swinging one of said jaws toward a closed position, whereby said racks will swing the remaining jaw toward a closed position, thereby causing said jaws to simultaneously clamp upon an article, and means moving onto said jaws as the jaws move to a closed position for reinforcing the jaws. 90 95

10. In a device of the class described, the 100 combination of a pair of gripping jaws, means for supporting said jaws, said jaws having intermeshing racks at their inner ends, means for swinging one of said jaws toward a closed position, whereby said racks 105 will swing the remaining jaw toward a closed position, thereby causing said jaws to simultaneously clamp upon an article, means for moving onto said jaws as the jaws move to a closed position for reinforcing the jaws, and 110 means releasably engaging the outer ends of said jaws for holding said jaws from accidentally opening.

11. In a device of the class described, the combination of a pair of gripping jaws, means for supporting said jaws, said jaws having intermeshing racks at their inner ends, means for swinging one of said jaws toward a closed position, whereby said racks will swing the remaining jaw toward a closed position, thereby causing said jaws to simultaneously clamp upon an article, reinforcing means partially fitting upon the inner ends of said jaws, and means engaging one of said racks and connected to said reinforcing means for moving said reinforcing means toward the center of said jaws as the jaws are moved to a closed position, thereby reinforcing said jaws so as to prevent their bending or springing when in use. 130

12. In a device of the class described, the combination of a pair of gripping jaws, means for supporting said jaws, said jaws having intermeshing racks at their inner ends, means for swinging one of said jaws toward a closed position, thereby causing said jaws to simultaneously clamp upon an article, and means releasably engaging the outer ends of said jaws when the jaws are 10 in a closed position for holding said jaws from accidentally opening.

13. In a device of the class described, the combination of a pair of gripping jaws, means for supporting said jaws, means for 15 moving said jaws to a closed position, and reinforcing means adapted to move onto said jaws while the jaws are being moved to a closed position, thereby reinforcing said jaws when strain is brought to bear upon 20 said jaws, whereby said jaws will be held from bending or breaking.

14. In a device of the class described, the combination of a pair of gripping jaws, means for supporting said jaws, means for 25 moving said jaws to a closed position, reinforcing means adapted to move onto said jaws while the jaws are being moved to a closed position, thereby reinforcing said jaws when strain is brought to bear upon 30 said jaws, whereby said jaws will be held from bending or breaking, and means releasably engaging the forward ends of said jaws when said jaws are in a closed position for holding said jaws from accidentally 35 opening.

15. In a device of the class described, the combination of a pair of gripping jaws, means for supporting said jaws, means for moving said jaws to a closed position, and 40 reinforcing means connected to said second-mentioned means, said reinforcing means moving onto said jaws as said jaws are swung to a closed position, thereby reinforcing said jaws when supporting strain is 45 brought to bear thereon.

16. In a device of the class described, the combination of a pair of gripping jaws, means for supporting said jaws, means for moving said jaws to a closed position, and 50 means releasably engaging the forward ends of said jaws when said jaws are in a closed position, thereby holding said jaws from accidentally opening.

17. In a device of the class described, the combination of a pair of gripping jaws, means for supporting said jaws, means for moving said jaws to a closed position, a locking slide mounted upon said first-mentioned means, said slide having a side rack, 60 a pinion meshing with said rack, means for rotating said pinion, whereby said locking slide will be moved into engagement with

the outer ends of said jaws when said jaws are closed, thereby positively preventing the opening of said jaws. 65

18. In a device of the class described, the combination of a pair of gripping jaws, means for supporting said jaws, means for moving said jaws to a closed position, said jaws having lugs extending from their forward ends, said lugs registering with each other when said jaws are in a closed position, and a locking slide removably fitting over said lugs for holding said jaws from accidentally opening. 70

19. In a device of the class described, the combination of a pair of gripping jaws, means for supporting said jaws, means for moving said jaws to a closed position, said jaws having lugs extending from their forward ends, said lugs registering with each other when said jaws are in a closed position, a locking slide positioned on said first-mentioned means in front of the outer ends of said jaws when said jaws are in a closed 85 position, said locking slide having a rack formed thereon, a pinion meshing with said rack, means for rotating said pinion, whereby as said pinion is rotated said slide will be moved into engagement with said lugs for 90 holding said jaws from accidentally opening.

20. In a device of the class described, the combination of a plate, jaws pivotally mounted upon said plate, intermeshing racks 95 formed upon the inner ends of said jaws, means for swinging said jaws to a closed position, a reinforcing plate slidably mounted upon the inner ends of said jaws, a pinion meshing with one of said racks, and means 100 connecting said pinion to said reinforcing plate, whereby as said jaws are swung to a closed position said reinforcing plate will be moved toward the center of said jaws.

21. In a device of the class described, the combination of a plate, jaws pivotally mounted upon said plate, intermeshing racks formed upon the inner ends of said jaws, means for swinging said jaws to a closed position, a reinforcing plate slidably mounted 110 upon the inner ends of said jaws, a pinion meshing with one of said racks, a slotted link pivotally mounted upon said plate and resting upon said pinion and reinforcing plate, a pin extending from said pinion, a pin extending from said reinforcing plate, said pins extending through said slotted link, whereby as said jaws are swung to a closed position said reinforcing plate will be moved toward the centers of said plates for 115 reinforcing the same. 120

In testimony whereof I hereunto affix my signature.

BENJAMIN FRANKLIN NIXON.
